A. F. COPERSITO.

FIREPROOF CASING FOR MOVING PICTURE FILMS.

APPLICATION FILED NOV. 8, 1915.

1,210,909.

Patented Jan. 2, 1917.

UNITED STATES PATENT OFFICE.

ANTHONY F. COPERSITO, OF BROOKLYN, NEW YORK.

FIREPROOF CASING FOR MOVING-PICTURE FILMS.

1,210,909.

Specification of Letters Patent.

Patented Jan. 2, 1917.

Application filed November 8, 1915. Serial No. 60,233.

To all whom it may concern:

Be it known that I, ANTHONY F. COPERSITO, a citizen of the United States, and a resident of Brooklyn, in the county of Kings and State of New York, have invented certain new and useful Improvements in Fire-proof Casings for Moving-Picture Films, of which the following is a specification.

My invention has for its object the production of a fire-proof casing for moving-picture films in which the reel on whose hub the film is wound itself forms essentially a portion of the casing.

A further object of my invention is the production of a casing of the character above described which shall be durable and simple in construction, of few parts and easily and cheaply manufactured.

As is well known, because of the inflammable nature of moving-picture films great care must be taken in shipping or storing the films to prevent their loss by fire, as some of them are worth a great deal of money and are easily destroyed. At present it is customary to ship or store the films after they have been wound on reels, the reel then being placed in a separate metal container or casing. By the use of my invention a small and compact casing is produced, the reel itself forming a part of the casing which is strictly fire-proof and is devoid of any cracks or crevices through which a flame could enter.

Other and further objects of the invention will appear from the subjoined description, the invention consisting in the novel features and parts and combinations of the same hereinafter more particularly described and then specified in the claims.

A practical embodiment of the invention is represented in the accompanying drawing forming a part of the specification in which similar characters of reference indicate corresponding parts in all the views.

In the drawing: Figure 1 represents a front elevation (partly broken away and partly in section) of my combined reel and fire-proof casing. Fig. 2 is a vertical cross-section taken on the line 2-2 of Fig. 1. Fig. 3 is a side elevation of the reel *per se* showing the lower portion thereof in section.

Referring more particularly to the several figures of the drawing: 1, 1 indicate two metallic imperforate disks joined at their centers, by suitable screws as shown, to the

hub 2 which may be either of metal or of wood with a sheet metal covering or collar. Each of the disks 1 is provided with a circular bead 3 extending completely around the disk and adjacent the inwardly flaring edges 4 thereof.

The hub 2 and disks 1 are provided with the usual opening or bearing 5 which is adapted to receive a shaft on which the reel 6 is carried. A portion of the hub 2 is cut away at 6 to form a depression for the screw-eyes 7 which carry a wire loop 8 to which an end of the flexible tape 9 is fastened. The flexible tape 9 is preferably 70 made of elastic and the buckle 10 is fastened to the other end thereof. When it is desired to wind a film 11 on the hub 2, an end of the film is passed through the buckle 10 which clasps the film and the reel is then 75 revolved on a shaft (not shown) which extends through the bearing 5. The flexible tape 9 carrying the film with it is then wound on the hub 2 and the film is wound around the tape as is clearly shown in Fig. 1. It is 80 the practice at present, when it is desired to wind a film on the hub of a reel, for the operator to fasten the end of the film to the hub by inserting his fingers through openings which are cut through the body of one 85 of the disks forming a part of the reel. This is an awkward and inconvenient operation, however, and would be impracticable and in fact impossible in the present case as the disks are imperforate for the reason that 90 they themselves form a part of the fire-proof casing for the film.

12 indicates a metallic band consisting of two semi-circular shaped members joined together by a hinge 13 whose flange portions are preferably fastened to the semi-circular shaped members by suitable rivets 95 as shown. The edges of the band 12 are adapted to fit over and engage snugly the edges of the disks 1, and the band forms 100 with the disks 1 a fire-proof casing for the film 11. Both edges of the band are provided with beads 13' and with flanges 14.

One of the semi-circular shaped members forming half of the band 12 is provided 105 with a spring latch 15 whose flange is secured to the semi-circular shaped member preferably by the rivets as illustrated. The spring latch 15 is provided with a perforation adapted to be engaged by a button 16 110 whose flange is attached to the other semi-circular shaped member preferably by suit-

able rivets as shown. By means of the latch and button both portions of the band 12 can be securely held together and the band can also be firmly clamped to the disks 1. When 5 the band 12 is clamped to the disks the inwardly flaring edges 4 of the disks 1 engage the inner surfaces of the flanges 14 and fit snugly within the depressions formed by the inner surfaces of the beads 13'. The edges 10 of the flanges 14 also partially engage the outer surfaces of the beads 3 of the disks 1.

17 and 18 indicate supplemental walls consisting of metal pieces securely fastened, as by the rivets as shown, to the inner 15 face of the band 12. The ends of these metal pieces extend over or span the meeting edges of the semi-circular shaped members comprising the band. The purpose of these supplemental walls is to cover any 20 space or opening which may be left between the meeting edges of the semi-circular shaped members through which a flame could enter so as to render the casing absolutely fire-proof in every respect.

25 20 indicates a name-plate which for convenience is secured, preferably by soldering, to the outer surface of the band 12, and which is provided in an edge thereof with a groove through which may be inserted a card or plate bearing the name of the particular film carried on the reel within the casing.

30 My invention is not limited to any particular form of clasp or latch for holding together the semi-circular shaped members of the band 12 on the disks 1 as any suitable clasp or latch could be used.

35 It will also be understood that the invention is not limited to the exact details of 40 construction and the arrangement of parts herein shown and described, such being for the purpose of illustration only, but various modifications may be resorted to without departing from the spirit of the invention 45 as set forth in the appended claims.

What I claim as my invention is:

1. A combined reel and casing for moving picture films consisting of a reel member comprising two imperforate metallic disks 50 each having a bead adjacent the outer edge, a hub to which said disks are secured and means for securing the film to the reel member, a band forming with said disks a casing for the film and comprising a plurality

of metallic members joined together and 55 provided with flanged edges and beads adjacent said flanged edges, said band members fitting over the edges of the disks so that the flanges engage the beads of the disks and the peripheries of said disks enter 60 the grooves of the beads of the band members.

2. A combined reel and casing for moving picture films consisting of a reel member comprising two imperforate metallic 65 disks each having an inwardly flaring portion at the outer edge, a hub to which said disks are secured and means for attaching the film to said hub, a band member forming with said reel member a casing for the 70 film and comprising a plurality of metallic members hinged together and provided with flanged edges and beads adjacent said flanged edges, said metallic members fitting over the edges of the disks so that the flanged 75 edges thereof bear on the flaring portion of the disks and the peripheries of the disks enter the grooves of the beads of said metallic members and means for locking the band member to the reel member. 80

3. A combined reel and casing for moving picture films consisting of a reel member comprising two imperforate metallic disks having inwardly flaring edges and annular beads adjacent said edges, a hub to 85 which said disks are secured and means for securing the film to said hub, a band member forming with said reel member a casing for the film and comprising a plurality of metallic members hinged together and 90 provided with flanged edges and beads adjacent said flanged edges, said metallic members fitting snugly over the flaring edges of the disks so that the flanged edges of said metallic members bear on the flaring edges 95 of the disks and the peripheries of the disks enter the grooves of the beads of said metallic members, supplemental metallic walls carried by the band members and spanning the meeting edges thereof and means for locking the band member to the reel member. 100

Signed at New York, in the county of New York and State of New York this 6th day of November A. D. 1915.

ANTHONY F. COPERSITO.
